SCOURING DEVICE

Filed March 7, 1927

UNITED STATES PATENT OFFICE

OTHO V. KEAN, OF PROVIDENCE, RHODE ISLAND

SCOURING DEVICE

Application filed March 7, 1927. Serial No. 173,425.

This invention relates to a functionally and structurally improved scouring device.

The present invention has to do more particularly with the class of scouring or scrubbing devices which are commonly used for cleaning and brightening the surfaces of metallic cooking utensils and other articles of like character in which the use of an abrasive material is desirable to remove substances which become caked thereon and to effect a thorough cleansing of the surfaces.

It is an object of the invention to provide a device of this character which will embody flexibility adequate to efficiently contact with all parts of the surface which is to be cleaned.

Another object is that of furnishing a scouring device, the construction of which will be simple and rugged to permit of the economical production of an article of this nature capable of use over relatively long periods of time.

Other objects of the invention will appear in the annexed specification taken in connection with the drawings, which latter illustrate practical embodiments of the invention and in which:—

Fig. 1 is an elevational view of one form which the structure may assume in practice,

Fig. 2 is an elevational view of a portion of the structure shown in Fig. 1, certain of the parts thereof being broken away to show their arrangements and the manner of connecting the free ends of the core,

Fig. 3 is an elevational view of a braided wire fabric, a portion thereof being expanded as for application to a core,

Fig. 4 is an elevational view of a modified form of the invention, and,

Fig. 5 is a detail sectional view illustrating the relative position of the core and enveloping fabric layers.

Broadly considered the improved structure shown and described herein involves the combination of a relatively larger core of resilient or elastic material, provided with a covering of abrasive material whereby the structure is given a high degree of flexibility which permits portions thereof to be forced into constricted spaces or depressions in the surface being cleaned and thereby enable

it to reach those portions of a surface which would not ordinarily be reached by the usual devices of this character. The resilient or elastic core may be of any desired shape, and may be formed of any suitable material, although, for the purpose of illustrating one embodiment thereof, I have shown a hollow rubber core as well adapted for the purpose. 55

The abrasive covering may be also formed of any suitable abrasive so arranged upon the core as to permit efficient operation of the device for the purpose specified, but I have found that a tubular woven or braided wire is well adapted for the purpose, and prefer to employ several layers of the abrasive material although under certain conditions and by the use of a mesh of sufficient coarseness a single layer of the abrasive material may be adequate for the purpose. As illustrating one form which the invention may assume in practice I may employ a woven or braided wire mesh of tubular form and of such size to enable it to be loosely sleeved over the resilient core, since this method of forming the structure may be readily employed and provides an efficient device for the purpose. 75

Referring to the form of scouring device shown in Figs. 1 and 2 of the drawings which is indicated generally by the numeral 1, 2 designates a resilient core of tubular form such as rubber hose of the usual or any suitable construction, one end 3 of the resilient core being compressed, slit or cut away to permit its insertion within the opposite end 4 thereof to provide a structure in the shape of an annulus. One or more layers of wire mesh are preferably applied to the core previous to the end 3 thereof being inserted within the end 4, as it is preferred to employ a woven or braided wire mesh of cylindrical shape for this purpose, and to sleeve the several layers of wire mesh over the core before the ends 3 and 4 are connected. However the several layers of wire mesh may be applied to the core after the ends of the core are connected. 95 The several layers of wire mesh, which in the present instance are three in number, although a greater or less number may be employed, are indicated by the numerals 5, 6, and 7. The wire mesh employed for this pur- 199

pose may be woven, braided, formed of links connected together, or made in any other desired manner, but in the present instance I have made use of a braided wire mesh which is initially formed as a flat braid 10 wherein the strands 11 lie in close proximity to each other. The wire is first expanded, as shown at 12, by being forced over a mandrel 13, or by other suitable means which separates the strands 11 to form a more or less loose mesh. After the braided wire has been expanded, as shown, several layers thereof are sleeved over the core 2, a sufficient length of the wire mesh being applied to the core to permit the same to be gathered loosely thereon, and a wire 14 may be wound about the structure to form a plurality of radial corrugations 15. After the wire mesh has been compressed in the direction of the length of the annulus and the surface thereof formed into corrugations by the application of the wire 14, the ends of the wire may be secured to each other or to the annulus and the wire retained thereon to permanently hold the wire mesh in position on the core, or the wire may be removed and the corrugations formed by the wire will be substantially retained in the mesh after the removal of the wire. The free ends of the tube and the various layers of wire mesh may be secured together in any suitable or desired manner, and the free ends of the wire 14 may be secured together or to the tube in any suitable way whereby the wire 14 will be securely held in place. The structure may be formed by first securing together the ends 3 and 4 of the core, and then covering the annulus with a plurality of layers of braided, woven, or linked wire mesh in sheet or strip form which may be wound therearound or applied in the form of spiral wrappings. Figs. 4 and 5 disclose a modified form of the invention wherein there is employed a resilient or elastic core 16 in the form of a sphere covered with a plurality of layers of wire mesh 17, 18, 19, in the form of woven, braided or linked wire mesh. The several cylindrical sections of wire mesh being preferably sleeved over each other to form a cylindrical section made up of a plurality of layers, and the spherical core 16 then inserted therein, and wire or cords 20 and 21 are wound about the sleeve adjacent to the ends thereof to draw the loose sleeve into the form shown in Fig. 4 having a plurality of corrugations 22 and loose end portion 23 which may serve as abrasive surfaces for reaching restricted parts of the surface to be cleaned. However, the structures shown in Figs. 4 and 5 may be formed by winding a sheet or strip of wire mesh into the form of a cylinder and then inserting the spherical core 16 therein and applying cords or wires 20 and 21 after the manner described. The wires or cords 20 and 21 may be secured to the wire mesh in

any desired manner to prevent their removal therefrom, and the ends of the cords or wires may be secured together in any suitable way. Thus, in each form of the invention it is preferable to apply the wire mesh loosely over the resilient core and hold the core thereon in such a manner as to form yielding corrugations adapted to bear against the surface to be cleaned. 70

From the above it will be seen that I have provided a scouring device capable of being easily constructed and possessing a considerable degree of resiliency, whereby it is made highly efficient for the purpose specified. 75

What I claim is:—

1. A scouring device comprising a core, a tubular wire mesh fabric, the strands of which are spaced from each other, said fabric being sleeved over the core and providing a plurality of circumferentially extending surface 80 corrugations. 85

2. A scouring device comprising a core, a wire mesh fabric sleeved over the core and having a plurality of surface corrugations, and a wire surrounding a portion of the wire mesh fabric and core and located between the corrugations for securing the wire mesh fabric to the cores. 90

3. A scouring device including a ring-shaped core and a separate reticulated metallic fabric enveloping said core, said fabric being of greater length than said core, the surface of such fabric being disposed in the form of corrugations to accommodate the entire length of such fabric upon said core. 95

4. A scouring device including a sleeve of reticulated abrading metal, a core disposed within said sleeve being materially in excess of the length of said core and the ends of said sleeve being disposed substantially adjacent the core ends, the surplus material of said sleeve being disposed in the form of corrugations having their innermost portions in contact with said core and said corrugations extending circumferentially of said 100 core. 105

5. A scouring device including a ring-shaped core having its ends connected, an abrading metallic reticulated fabric tube member sleeved upon said core, the length of said fabric being normally in excess of the major circumference of said core, the surplus fabric material being disposed in the form of corrugations around said core. 110 115

In testimony whereof I have affixed my 120 signature.

OTHO V. KEAN.
